TO ACKERMAN-BLAESSER-FEZZEY, INC., OF DETROIT, MICHIGAN, A CORPORATION
OF MICHIGAN

CLUTCH DEVICE

Application filed March 23, 1928. Serial No. 264,120.

This invention relates to clutch devices and the object of the invention is to provide a device for use in connection with a window regulator so arranged as to allow rotation at any time of the crank for operating the window regulator but preventing operation of the window regulator by pressure applied to the window.

Another object of the invention is to provide a clutch device comprising a coiled spring positioned within a casing and adapted to be contracted by rotation of the crank and adapted to be expanded into binding engagement with the wall of the casing by pressure applied to the window or parts attached thereto.

A further object of the invention is to provide a clutch device for use with a window regulator in which the window is automatically locked in position at any point to which it is adjusted.

These objects and the several novel features of the invention are hereinafter more fully described and claimed and the preferred form of construction by which these objects are attained is shown in the accompanying drawings in which—

Fig. 1 is an elevation of an automobile door with which the clutch device is utilized.

Fig. 2 is a view of the inner side of the clutch device.

Fig. 3 is a section taken on line 3—3 of Fig. 2.

Fig. 4 is a section taken on line 4—4 of Fig. 3 and showing the operating members in the neutral position.

Fig. 5 is a view similar to Fig. 4 showing the operating members during rotation.

Fig. 6 is a perspective view of the operating device.

Fig. 7 is a perspective view of the locking member.

As shown in Figs. 2 and 3, the device comprises a sheet metal casing 1 having a peripheral flange 2 about the outer edge. This flange is provided with an arcuate depressed portion 3 and the flange is also provided with apertures 4 by which the device may be secured to an automobile door frame. The member 1 is cup shaped in form and is pro-

vided with an inverted cup shaped member 5 positioned therein as shown in Fig. 3. Within the cylindrical wall of the housing 1 a coiled spring 6 is positioned and normally fits tightly against the inner wall of the casing so that it cannot be readily rotated therein. A shaft 7 is provided which is rotatably mounted in the end 8 of the casing and this shaft is provided with a squared end 9 to which a crank may be secured. As shown in Figs. 3, 4 and 6 a member 10 is secured to the shaft 7 and is provided with two depending lugs 11, shown more particularly in Fig. 6. These lugs 11 extend downwardly within the coiled spring 6, as shown in Fig. 4, and the coiled spring 6 is provided with an inturned upper end 12 and an inturned lower end 13. By this arrangement when the shaft 7 and member 10 is turned in one direction one lug 11 engages the end 12 of the spring thus contracting the spring and allowing the spring to turn in the casing with the member 10 and shaft 7. Upon rotation of the shaft and member 10 in the opposite direction the other depending lug 11 engages the lower inturned end 13 of the spring 6 and this turning movement of the member 10 contracts the spring and allows the spring to turn in the casing with the member 10. The shaft 7 is provided with an extending stud 14. A gear 15 shown in Figs. 2 and 7 is rotatably mounted on the stud 14 and is provided with a member 16 secured thereto as shown in Figs. 3 and 7 and the member 16 is provided with two depending lugs 17 shown in Figs. 3, 4, 5 and 7. The member 16 is provided with two upturned lugs 18 which are pressed into notches provided therefor in the gear 15 and secure the member 16 to the said gear. The member 16 and gear 15 are each provided with an aperture for the stud 14 and are positioned over the stud 14 with the depending lugs 17 extending into the spaces between the spring ends 12 and 13 and the ends 23 and 24 of the flange 19 on the member 10. The gear 15, as shown in Fig. 3, meshes with the gear segment 20 which is adapted to be turned to turn the window regulator arm 21 to raise or lower the window. The flange 19 on the

member 10 and the lug 22 extending from the opposite side of the member 10 extend over the edge of the spring 6 and form a retainer to retain this spring in the casing 1. The member 16 and gear 15 are positioned over the stud 14 with the lugs 17 extending into the position shown in Fig. 4. Upon rotation of the shaft 7 in a counter clockwise direction the lug 11 of the member 10 first 10 engages the spring end 12 causing the spring to contract and the end 23 of the flange 19 engages one of the lugs 17 as shown in Fig. 5 thus turning the member 16 and gear 15 with the member 10 and the shaft 7. Upon 15 rotation of the shaft in the opposite direction the opposite lug 11 of the member 10 engages the spring end 13 thus contracting the spring and the end 24 of the flange 19 engages the opposite lug 17 and carries the member 16 and gear 15 with the member 10. Thus upon rotation of the shaft 7 in either 20 direction the member 16 and gear 15 are picked up and rotated with the shaft thus turning the gear segment 20 which meshes 25 with the gear 15 in raising or lowering the window. The gear 15 and member 16 are free to rotate to a limited extent in relation to the member 10 by downward pressure applied to the window and through the regulator arm 21 to the gear segment 20. Rotation 30 of the gear 15 by the gear segment 20, however, is prevented as the rotation of the gear 15 in this manner in one direction moves the lug 17 at the left of Figs. 4 and 5 into 35 engagement with the spring end 12 thus tending to expand the spring into binding engagement with the inner wall of the casing 1 and preventing such rotation. Rotation 40 of the gear 15 in the opposite direction is prevented by the opposite lug 17 engaging the spring end 13 and tending to expand the 45 said spring into binding engagement with the casing wall. The parts are so arranged, as will be understood from Figs. 4 and 5, 50 that when the shaft 7 is rotated to contract the spring, the end 23 of the flange 19 engages the lug 17 at the right side of Figs. 4 and 5 before the spring end 12 engages the opposite lug 17 and upon rotation in the 55 opposite direction the end 24 of the flange 19 engages the lug 17 at the left of Figs. 4 and 60 5 just before the opposite lug 17 is engaged by the spring end 13 and thus when the shaft 7 is rotated the member 16 and gear 15 are 65 carried by the shaft without locking engagement with the spring ends 12 or 13. It will be noted that when the gear 15 is rotated by the gear segment 20 that the greater the pressure applied to the gear 20 the greater pressure 70 is applied to the spring ends 12 or 13 thus expanding the coiled spring with greater pressure and causing it to bind more tightly in the casing to prevent rotation of the gears. As will be noted from Fig. 3 the end 75 14 of the shaft 7 extends beyond the flange

2 and is rotatably mounted in an aperture provided therefor in the frame member to which the casing is attached. This provides a support for the outer end of the shaft 7 while the shaft is rotatably mounted at the 70 opposite end in the portion 8 of the casing. In order to prevent wear between the member 5 and the member 10 a hardened steel washer 23 is secured to the shaft 7 immediately behind the member 10 as shown in Fig. 75 3 and rides in contact with the stationary member 5.

From the foregoing description it becomes evident that the device is very simple and efficient in operation, is composed of few 80 parts and is of consequent low manufacturing cost, will lock a window at any point to which it is adjusted and provides a device which accomplishes the objects described.

Having thus fully described our invention, 85 its utility and mode of operation, what we claim and desire to secure by Letters Patent of the United States is—

1. In a clutch device, a casing, a shaft rotatably mounted in the casing, a coiled 90 spring positioned in the casing and frictionally engaging the wall of the casing, the ends of the spring being bent inwardly, a member secured to the shaft having a pair of lugs extending between the ends of the coiled 95 spring, the arrangement being such that rotation of the said member in one direction causes one of the lugs to engage one end of the spring and contract the spring and rotation of the said member in the opposite direction causes the other lug to engage the opposite end of the spring and contract the spring, the said member being provided with a lug between the first two lugs extending over the spring and retaining the spring in 105 the casing, the said member being also provided with a flange opposite the said lug extending over the spring and retaining the spring in the casing, a second member rotatable in relation to the first member and having a pair of lugs extending within the spring between the ends of the flange of the first member and the ends of the spring, the arrangement being such that rotation of the second member in relation to the first member 110 moves one of the lugs into engagement with one end of the spring and expands the spring, and rotation of the second member in the opposite direction in relation to the first member moves the other 115 lug into engagement with the opposite end of the spring to expand the spring, rotation of the said first member in either direction causing one end of the flange to engage one of the lugs of the second member to carry 120 the second member with the first member, and a gear secured to the second member.

2. In a clutch device, a casing having an open end, a shaft rotatably mounted in the casing, a member secured to the shaft and 130

having a pair of lugs extending into the casing from the open end, a second member rotatably mounted on the shaft and having a pair of lugs also extending into the casing 6 from the open end, a coiled spring positioned in the casing and frictionally engaging the wall of the casing, the said spring having in-turned ends extending between the lugs of the first and second members respectively, the 10 first member being adapted to carry the second member therewith during rotation of the first member, the arrangement being such that rotation of the shaft and the first member in either direction moves one of the lugs 15 of the first member into engagement with one of the ends of the spring to contract the spring and rotation of the second member in either direction in relation to the first member moves one of the lugs of the second member 20 into engagement with one end of the spring to expand the spring into binding engagement with the wall of the casing, the first member being formed to retain the spring in the casing and a gear secured to the said second member. 25

3. In a clutch device, a casing, a shaft rotatably mounted therein, a coiled spring positioned within the casing for frictionally engaging the inner walls thereof, said spring 30 having ends extending radially inward, a member secured to the shaft having a pair of lugs extending between the ends of the coiled spring, a second member rotatably mounted relative to the first member and in side by 35 side relationship and having a pair of lugs extending upon opposite sides of the spring ends from that of the lugs of the first member, the lugs and spring being so arranged that rotation of the second member in either 40 direction in relation to the first member causes the respective lug thereof to engage a spring end and expand the same to binding engagement with the inner wall of the casing, a gear secured to the said second member 45 and means whereby rotation of the first member in either direction causes a lug to engage its spring and to contract the spring and thereby free the parts to rotation. 50

4. In a clutch device, a hollow cup-shaped casing having an open end, an inverted cup-shaped member positioned concentrically therewithin less in length than the outer casing and spaced from the wall thereof, a shaft rotatably mounted on the axis of and within 55 the casings and extending therethrough, a member secured to the shaft to rotate therewith and having lugs extending inwardly between the two cupped members from one end, a second member having lugs also extending 60 into the space between the two said cupped members from the same end of the casings as the first named lugs, the lugs of the two members being in spaced relation, a coiled spring in the outer casing within which the lugs are 65 positioned, said spring having ends extend- ing radially inward and positioned between lugs of the respective members, the relationship of the said members, lugs and spring being such that rotation of the shaft and the attached first member contracts the spring 70 freeing the same to rotation within the casing and rotation of the second member relative to the first expands the spring to frictional engagement with the walls of the outer casing, the said inner cupped member acting 75 as a spacer to hold the said first and second members from movement longitudinally inwardly of the outer casing. 80

In testimony whereof we sign this specification.

EDWARD L. ACKERMAN.
